UNITED STATES PATENT OFFICE

HARRY LEBERMAN, OF NEW YORK, N. Y., ASSIGNOR TO GROOVE LOCK CO. INC., OF NEW YORK, N. Y., A CORPORATION OF NEW YORK

FASTENING DEVICE FOR POCKETBOOKS AND THE LIKE

Application filed January 22, 1929. Serial No. 334,336.

My invention relates to fastening devices, the invention being more particularly related to an improved construction of this character for use in connection with pocketbooks and similar containing devices.

Among the objects of my invention is to provide an improved fastening device of this character which is attractive in appearance, simple and rugged in construction, not liable to get out of order and positive and efficient in operation.

An object of the invention is to provide fastening means of the kind referred to and in a manner as hereinafter set forth, whereby readily and detachably to secure together the side members or sections of a pocket book which are constructed and connected to close in substantially flatwise relation.

Another object of the invention is to provide fastening means of the character described, in which the locking element is arranged for sliding movement and must be bodily slid into a particular position for escape through an opening in the securing element or keeper therefor, before the pocketbook can be opened. By this construction, requiring positive bodily movement of the locking element, the pocketbook is prevented from opening accidentally.

Other objects will appear hereinafter.

The invention consists of the parts and combination or combinations of parts herein-after described and set forth in the appended claims.

The invention will be best understood by reference to the accompanying drawing, forming a material part of the specification, and in which—

Fig. 1 represents a plan and edge elevation, showing the side members of a pocketbook secured together in flatwise relation by my improved fastening device;

Fig. 2 represents a perspective view, showing the side members in partially open relation to disclose the co-operating parts of my fastening device;

Fig. 3 represents a right hand edge elevation of the parts as they appear in Fig. 1;

Fig. 4 represents a detail view, showing

on a larger scale a longitudinal section on the line 4—4 of Fig. 1;

Fig. 5 represents another detail view, showing on a larger scale a transverse section on the line 5—5 of Fig. 1; and

Fig. 6 represents a detail perspective view, showing more fully the construction of the rail and sliding button thereon.

In the exemplification shown in the accompanying drawing, my improved fastening device is illustrated in connection with a pocketbook structure comprising side members or sections 10 and 11 edge connected at 12 for opening and closing movement in a conventional manner.

My fastening device, in its preferred form of construction, comprises a locking element in the form of a button 13 mounted for sliding movement along the inner face of the side member 10, and a keeper for the button in the form of a securing plate 14 which is incorporated in the other side member 11. The button 13 is slidably mounted upon the head 15 of a rail 16 formed with a base plate 17 which is adapted to fit flat upon the inner face of the side member 10. In order to be secured to the side member 10, the base 17 of the rail is shown herein as provided with oppositely directed plate-like projections 18 which extend well beyond the ends of the rail and adjacent their connection with the rail are bent outwardly therefrom at 19 in order to lie in a plane parallel with the base 17 so as to be embedded within the body of the material of the side member 10, whereby firmly to secure the rail in place with its base 17 in flatwise contact with the side member.

In order to be secured to the rail for sliding movement thereon, the button is represented as being provided with opposing flange members 20 which are bent to conform with the shape of the head 15 of the rail so as to slidingly embrace the same. Preferably and as shown, the head 15 of the rail is provided with suitable stop members 21 and 22, designed to define the range of movement of the button upon the rail.

The securing means or keeper 14 is illustrated as composed of an outer plate 23 and

an inner plate 24 connected by inner transverse walls 25 arranged to define a longitudinally extending slot 26 expanded at one end to provide an escape opening 27 for the button. The securing means or keeper 14, thus made, is mounted in the side member 11 after the manner in which an eyelet device is incorporated in material, the longitudinally extending slot 26 and accompanying opening 27 providing a transverse passageway through the side member 11 while the outer and inner plates 23 and 24 embrace the side member 11 so as to fix the securing means or keeper 14 in its entirety thereon.

According to a feature of my invention, the head 15 of the rail is adapted to enter the longitudinally extending slot 26 with its accompanying opening 27 when the side members 10 and 11 are swung into flatwise relation as illustrated in Fig. 1; and it is to be observed in this connection that when the rail head 15 has been entered in the elongated slot 26 there is sufficient clearance space for the flange members 20 to allow the button to be moved freely along the rail between the walls 25 which connect the outer and inner plates 23 and 24. The opening 27 is of such size that the button 13 can readily be passed transversely therethrough as the rail head is entered in the slot 26 and accompanying opening 27 upon the closing of the side members 10 and 11.

While the button can be freely passed through the opening 27 and slid along the rail from said opening into the longitudinally extending slot 26, it is provided with means whereby upon entering the slot 26 a sliding interlocking action will take place between the button and the outer plate 23 so as to prevent the withdrawal of the button laterally through the slot 26 by reason of the opening movement of the side members 10 and 11. To this end the button is represented as being formed with shoulders 28 adapted to slidably engage over the outer plate 23 at opposed sides of the longitudinally extending slot 26 therein. According to another feature of my invention, block-like members 29 are suitably connected between the rail 16 and its base 17 in such position that centering projections 30 will enter the opening 27 when the side members 10 and 11 are closed; and other suitable blocks 31 having centering projections 32 adapted to enter the slot 26, are also fixed to the rail and its base. By means of the centering projections 30 and 32 the rail head is so maintained in the button securing means or keeper that the button may be freely moved along the rail head without any binding action. When the button is moved into engagement with the stop 21, it will be in position to pass through the opening 27 upon the closing of the side members 10 and 11. The other stop member 22 is so located

that the button, upon engaging the same, will occupy a position substantially midway the length of the securing means or keeper. In this way, provision is made to limit the range of movement of the button and to define the limit of its locking position as well as to define the particular position in which it may be passed through the escape opening 27.

In use, it will be apparent that the button is moved along the rail until it engages the stop 21 whereupon it can be entered through the opening 27 upon the closing of the side members 10 and 11; and from the opening 27 the button, owing to the provision of the centering projections 30 and 32 which maintains the rail in proper relation to the walls 20, can be freely moved into the longitudinally extending slot 26 where its shoulders 28 interlock with the outer plate 23 so as to secure the side members 10 and 11 together in flatwise relation. In order to permit the opening movement of the side members 10 and 11, it is only necessary to move the button from the slot 26 into the escape opening 27.

From the above description, taken in connection with a study of the accompanying drawing, it will be understood that I have provided a simple, strong and durable fastening device for pocketbooks and like containing structures, one which will perform the functions for which it is intended with ease and efficiency, and one which possesses the advantage of positively not permitting the pocketbook to be opened until the button has been bodily moved into position to escape through the opening 27.

While I have illustrated and described the preferred form of construction for carrying my objects into effect this is capable of variation and modification without departure from the spirit of the invention. I, therefore, do not wish to be limited to the details of construction herein set forth, but desire to avail myself of such variations and modifications as come within the scope of the appended claims.

I claim:

1. A fastening device for the purpose set forth comprising a rail having base portions and a head, a button slideable along the head of the rail, a securing plate provided with a guide slot and an opening, both being entirely through the plate transversely thereof and defined by edge walls which extend from the inner face of the plate to the outer face thereof, the head of the rail being insertable between the edge walls of the slot and opening so as to permit the inner face of the plate to rest upon the base portions, said button being insertable through the opening and constructed to have sliding contact between the head of the rail and the edge walls of the slot, and projections on the button adapted to slide in contact with the outer face of the plate.

when the inner face of the plate rests on said base portions.

2. A fastening device for the purpose set forth comprising a rail and a headed button 5 slidable along the top of the rail and having opposing flanges slidably embracing the opposite sides of the rail, a securing plate for the rail and button, provided with a guide slot and an opening at one end of the guide 10 slot, the opening being of greater cross dimension than that of the guide slot, the head of the button being insertable through said opening and the rail being insertable in the opening and slot to occupy a position between 15 the longitudinal edge walls which define the opening and slot, the opposing flanges of the button adapted to have sliding engagement between the rail and longitudinal edge walls of the slot, and the head of the button being 20 shaped to have sliding contact with the outer face of the plate at opposite sides of said slot.

3. A fastening device for the purpose set forth comprising a rail with a head and a button slidable along the top of the head of the rail and having opposing flanges slidably embracing the opposite sides of the head of the rail, lateral projections on the button extending beyond the faces of the flanges, a securing plate for the rail and button, provided 25 with a guide slot and an opening at one end of the guide slot, the opening being of greater dimension than that of the slot, the head of the rail being insertable in the opening and slot to occupy a position between the longitudinal edge walls which define the opening and slot, centering projections on the rail 30 adapted to fit between the longitudinal edge walls of the opening and slot respectively, the opposing flanges of the button adapted 35 to have sliding engagement between the sides of the rail head and the longitudinal edge walls of the slot, the button with its lateral projections being insertable through said 40 opening as the centering projections are seated between the aforesaid edge walls, and the said lateral projections on the button, when 45 said centering projections are seated and on the movement of the button into the slot, being adapted to have sliding contact 50 with the outer face of the plate.

4. A fastening device for the purpose set forth comprising a rail having subjacent base portions at its opposite sides, a button 55 slidable along the top of the rail and having opposing flanges slidably embracing the opposite sides of the rail above the base portions, lateral projections on the button extending beyond the outer faces of the flanges, 60 a securing plate for the rail and button, provided with a guide slot and an opening at one end of the guide slot, the opening being of greater cross dimension than the guide slot, the button with its lateral projections 65 being insertable through said opening and

the rail being insertable in the opening and slot to occupy a position between the longitudinal edge walls which define the opening and slot, and to permit the securing plate to rest on said base portions, the opposing flanges of the button adapted to have sliding engagement between the rail and the edge walls of the slot, and said lateral projections on the button, when said plate rests on said base portions and on movement of the button into the slot, being adapted to have sliding contact with the outer face of the plate.

In testimony that I claim the foregoing as my invention, I have signed my name 80 hereto.

HARRY LEBERMAN.
